(57) **CLAIM**

I claim the ornamental design for a handheld tool for providing cooling therapy to a skin surface, as shown and described.

DESCRIPTION

FIG. 1 is a top front isometric view of a handheld tool for providing cooling therapy to a skin surface showing my new design;

FIG. 2 is a bottom front isometric view thereof;

FIG. 3 is a front elevation view thereof;

FIG. 4 is a top plan view thereof; and,

FIG. 5 is a bottom plan view thereof.

A rear elevation view and a side elevation view have been omitted, as it is a mirror image of the front elevation view of FIG. 3.

The broken line shown in the drawings is included for the purpose of illustrating portion of the handheld tool for providing cooling therapy to a skin surface and forms no part of the claimed design.
